UNITED STATES PATENT OFFICE.

CARRIE BRANDT PETERSON, OF KNOXVILLE, ILLINOIS.

SKIRT-SUPPORTER AND SHIRT-WAIST HOLDER.

SPECIFICATION forming part of Letters Patent No. 758,146, dated April 26, 1904.

Application filed October 19, 1903. Serial No. 177,659. (No model.)

To all whom it may concern:

Be it known that I, CARRIE BRANDT PETERSON, a citizen of the United States, residing at Knoxville, in the county of Knox and State of Illinois, have invented certain new and useful Improvements in Skirt-Supporters and Shirt-Waist Holders, of which the following is a specification.

The present invention relates to a device for supporting the back of the skirt to prevent it from sagging and at the same time holding down the back of the shirt-waist to prevent it from riding up. Such a device usually comprises a metallic plate of sufficient flexibility to enable it to conform freely to the waist, means carried by the plate for engaging the skirt and waist for supporting the one and holding the other down, and a two-part band, each part attached to the ends of the plate and the two parts being adapted to be tied, buckled, or otherwise fastened together in front.

The objects of the invention are to provide a device of this class of simple and inexpensive construction that will not injure the garments, that may be easily and quickly manipulated, that is effective for the purposes intended, that (when desired) transfers the weight of the skirt from the waist, hips, and neck to the shoulders and front of the corset, and that holds the skirt straight.

To these ends the invention consists in the features of novelty that are hereinafter described with reference to the accompanying drawings, which are made a part of this specification, and in which—

Figure 1 is an elevation of the base-plate without shoulder-straps, waistband, or buttons. Fig. 2 is an elevation of one form of the improved device. Fig. 3 is a similar view of a modification. Fig. 4 is a similar view of still another modification, this being elected as the preferred form for the purposes of this application. Fig. 5 is a detail view of the front portions of the shoulder-straps.

A represents the base-plate, which is preferably made of a strip of thin sheet-aluminium that will bend easily and conform to the waist. It is provided near each of its ends with two vertical parallel slots B, leaving between them

a bar C, around which one end of each of the two parts of a waistband D passes and is secured by stitching, a buckle, or other means, the other ends of said two parts being adapted to be tied or otherwise fastened in front of the wearer.

E represents buttons carried by the base-plate and adapted to be passed through buttonholes provided for them in the garment or garments. These buttons may be of any desired number and located in any desired positions. In the drawings three, located one in the center and one near each end, are shown. Furthermore, they may be of any desired construction, but preferably are in the form of studs permanently secured to the plate and having enlarged heads. The base-plate also has near each of its ends two horizontal slots F, providing a horizontal bar G, around which bars the ends of shoulder-straps H are passed and secured by any suitable means. These straps pass over the shoulders, and their forward ends are united to a single piece I, having eyelets J, any one or more of which is adapted to be engaged by a stud or studs on the corset-stay, and by this means shoulder-straps of a given length are adapted for use by persons of different heights. The shoulder-straps give a firm support to the base-plate and throw the weight of the garment or garments onto the shoulders and front of the corset, thus relieving the hips, waist, and neck.

The device may be used with both the waistband and shoulder-straps, as shown in Fig. 4, or with either alone.

The base-plate is provided also along its lower margin with a row of perforations K for enabling a bustle L to be stitched or otherwise secured to it.

What I claim as new, and desire to secure by Letters Patent, is—

A device of the class described having a base-plate provided near each of its ends with vertical slots leaving between them a vertical bar and with horizontal slots leaving between them a horizontal bar, a waistband passing through the vertical slots and held by the vertical bars, shoulder-straps passing through the horizontal slots and held by the horizon-

tal bars, said shoulder-straps being continued from the shoulders and downward in front of the wearer, a single strap to which the front ends of the shoulder-straps are secured, said 5 single strap having eyelets adapted to be engaged by a stud or studs on the corset-stay, and buttons carried by the base-plate and

adapted to engage the garment or garments, substantially as described.

CARRIE BRANDT PETERSON.
